(57) **CLAIM**

The ornamental design for a motorcycle fork lock cover, as shown and described.

DESCRIPTION

FIG. 1 is a perspective view of the front of the motorcycle fork lock cover of this invention in the closed position,

FIG. 2 is a perspective view similar to that shown in FIG. 1 of the motorcycle fork lock cover on a reduced scale while in use on a motorcycle, which is shown in broken lines for purposes of illustration only and forms no part of the claimed design,

FIG. 3 is a perspective view of the front of the motorcycle fork lock cover of this invention shown in a 12 o'clock open position,

FIG. 4 is a perspective view of the back of the motorcycle fork lock cover of this invention in the closed position, FIG. 5 is a perspective view of the back of the motorcycle fork lock cover of this invention in the 12 o'clock open position,

FIG. 6 is a plan view of the front of the motorcycle fork lock cover of this invention shown in a 9 o'clock open position, FIG. 7 is a plan view of the front of the motorcycle fork lock cover of this invention shown in a 12 o'clock open position, FIG. 8 is a plan view of the front of the motorcycle fork lock cover of this invention shown in a 3 o'clock open position, FIG. 9 is a plan view of the back of the motorcycle fork lock cover of this invention shown in a 3 o'clock open position, FIG. 10 is a plan view of the back of the motorcycle fork lock cover of this invention shown in a 12 o'clock open position, and

FIG. 11 is a plan view of the back of the motorcycle fork lock cover of this invention shown in a 9 o'clock open position.

FIG. 12 is a side elevational of the motorcycle fork lock cover of this invention view taken from the left hand side as view in FIG. 6.

FIG. 13 is a side elevational view of the motorcycle fork lock cover of this invention taken from the right hand side as view in FIG. 6.

FIG. 14 is a bottom view of the motorcycle fork lock cover of this invention taken form the bottom as view in FIG. 6.

FIG. 15 is a top view of the motorcycle fork lock cover of this invention taken from the top as view in FIG. 6.

FIG. 16 is a side elevational view of the motorcycle fork lock cover of this invention taken from the left hand side as view in FIG. 7.

FIG. 17 is a side elevational view of the motorcycle fork lock cover of this invention taken from the right hand side as view in FIG. 7.

FIG. 18 is a top view of the motorcycle fork lock cover of this invention taken form the top as view in FIG. 7.

FIG. 19 is a bottom view of the motorcycle fork lock cover of this invention taken from the bottom as view in FIG. 7.

FIG. 20 is a side elevational view of the motorcycle fork lock cover of this invention taken from the left hand side as view in FIG. 8.

FIG. 21 is a side elevational view of the motorcycle fork lock cover of this invention taken from the right hand side as view in FIG. 8.

FIG. 22 is a bottom view of the motorcycle fork lock cover of this invention taken from the bottom as view in FIG. 8.

FIG. 23 is a top view of the motorcycle fork lock cover of this invention taken from the top as view in FIG. 8.

FIG. 24 is a plan view of the motorcycle fork lock cover of this invention in a closed position.

FIG. 25 is a side elevational view of the motorcycle fork lock cover of this invention taken from the left hand side as view in FIG. 24.

FIG. 26 is a side elevational view of the motorcycle fork lock cover of this invention taken from the right hand side as view in FIG. 24.

FIG. 27 is a side elevational view of the motorcycle fork lock cover of this invention taken from the top as view in FIG. 24; and,

FIG. 28 is a side elevational view of the motorcycle fork lock cover of this invention taken from the bottom as view in FIG. 24.
